RETURN LETTER-FORM

Henry Parr, New York, N. Y.

Application May 6, 1931, Serial No. 535,407

6 Claims. (Cl. 229—92.7)

My invention relates to a return letterform; that is, a novel and improved printed paper blank designed for folding and re-folding in such manner as to provide facility for use as a return message or reply to the sender.

As otherwise described, the invention consists in a return envelope including a message or letter-sheet bearing any desired advertising or other subject matter and arranged for insertion 10 by the recipient of his name and address and/or other data, and designed also for convenient re-folding into envelope form whereupon the proper return address is exposed.

The invention thus provides in novel and improved form a simplified and inexpensive substitute for a sending envelope, letter sheet or advertising pamphlet, and return envelope, as commonly used in circularizing customers and for analogous purposes.

The characteristics and advantages of the invention are further sufficiently explained in connection with the following detail description of the accompanying drawings, which show one preferred embodiment. After considering this example, skilled persons will understand that many variations may be made without departing from the principles disclosed; and I contemplate the employment of any structures or arrangements that are properly within the scope 40 of the appended claims.

Fig. 1 is a plan view of one face of a blank embodying the invention in one form.

Fig. 2 shows the opposite face of the blank.

Fig. 3 shows the blank partly folded in preparation for first mailing.

Fig. 4 shows the blank in further folded condition.

Fig. 5 shows the blank in fully folded condition ready for the first mailing.

Fig. 6 shows the blank partly refolded in preparation for the second or return mailing.

Fig. 7 shows a subsequent stage of the refolding operation.

Fig. 8 shows the blank or envelope in fully folded condition, ready for re-mailing to the original sender.

The blank as shown in Figs. 1 and 2 is of paper of suitable quality for the purpose in view. Fig. 1 shows the face of the blank which may be called the "inner face", since most of its portions are normally enclosed or concealed. Fig. 2 shows the outer face, including portions some of which are exposed in original mailing and other portions are exposed in remailing.

The blank includes a main sheet portion 1,

usually of rectangular form, corresponding substantially to a letter sheet, to carry on its inner face the desired communication, as to a prospective customer or client; although of course the indicia imprinted on the inner face of the sheet 60 may vary widely. As shown, the indicia 2 is intended for circularizing a certain class of customers and includes blanks or ruled lines 3 for insertion of certain data by the customer or original addressee of the letter, and also indicia 4 65 calculated to induce the insertion of his name or signature in the space 5.

This main portion, which for convenience is sometimes called the letter or message sheet, is intended to be folded on the lines 6, 7 and 8; 70 and in some cases any or all of these lines may be imprinted on one or both faces of the blank; otherwise, and usually, the lines as shown in the drawings are only for explanatory purposes, except with respect to that portion of the line 6 75 between the lines 7 and 8; this may be imprinted on the outer face of the blank, Fig. 2, as a "solid" or dotted line.

The stated lines 6, 7 and 8 divide the main sheet into spaces or sections 10, 11, 12, 13, 14 and 80 15. The lines 7 and 8 also define end flaps 16 and 17, of which 16 includes the portions 12 and 13, and 17 includes the portions 14 and 15. These are referred to as end flaps since they constitute upper and lower end portions of the main sheet 85 when positioned for reading as in Fig. 1. The portions 10 and 11 occupy the central area of the main sheet. At one side of the main sheet and co-extensive with this portion 10 is an integral short side flap 20, usually having its ends diagonally cut, as at 21. This is to be folded along the line 22 which appears in the drawings but need not be imprinted on the blank.

At the opposite side, there is an integral wide flap 23 and this terminates in an integral short 95 flap 24 similar to the flap 20, the flaps 20 and 24 constituting principally sealing flaps, as will appear. Flap 23 is to be folded at the line 25 and flap 24 is to be folded in relation to flap 23 at the line 26; and these lines 25 and 26 appear on 100 the drawings for purposes of explanation but need not be imprinted on the blank, except with respect to the line 26, which is desirably imprinted on the outer face of the blank, Fig. 2, usually in the form of a dotted line with the adjacent legend "cut along the top" as shown in Fig. 2, this being a direction to the original recipient or addressee of the form. Flap 24 also has its ends diagonally cut as at 27.

The sealing flaps 20 and 24 have on their inner 110

faces, Fig. 1, marginal stripes of adhesive 28 and 29 respectively, these usually extending along the main and diagonal margins as in the case of an ordinary envelope flap.

5 The main sheet space or area 10 has on its outer face, Fig. 2, indicia 30 constituting the return address and will usually be also designed for "postage prepaid" purposes, having for that purpose the authorized imprint 31 in lieu of a stamp 10 and also the explanatory imprint 32; or evidently subject matter on this part of the blank may be varied. The outer face (Fig. 2) of flap 23 is intended for the original address, that is, the address to be applied by the original sender of the 15 communication to a customer, and usually has the imprinted return address 33.

In preparation for first mailing, the original addressee's name and address may be filled in as at 34, Fig. 1, on the inner face of the main 20 sheet portion 11; or this item may of course be omitted. The name and address of the addressee are filled in as at 35 on the outer face of the flap 23 (Fig. 2). The blank is then ready for first 25 folding for the first mailing. These operations are well explained in Figs. 3 and 4. The end flaps or portions 16 and 17 are first folded over upon the portions 10, 11 and the short flap 20 is folded over upon the end portions 16 and 17 at one end thereof, as shown in Fig. 3, the adhesive 28 of this 30 flap 20 being at this time not moistened so that there is no adhesive attachment. The main portion of the sheet is then folded along the line 6 so that the portions 12 and 13 are brought into facial contact respectively with the portions 14 35 and 15, the flap 20 being interposed between parts of the stated portions. As shown in Fig. 4, this presents the return address imprint 39 on blank portion 10 uppermost, and that portion is then covered by folding down the broad flap 23 and 40 then folding the connected narrow flap 24 about the edge of the portion 10, moistening and securing the adhesive 29 to complete the closure of the envelope-sheet. The first or original sending address 35 then appears on one outside face 45 of the package which is the outer face of the blank portion 23 as shown in Fig. 5, and all other subject matter is enclosed and concealed.

When delivered to the addressee, he observes 50 the legend "cut along the top" or any equivalent direction appearing adjacent the imprinted opening line 26, and when the paper is cut at this line, the blank may be opened out to the position and condition of Fig. 1 except that the flap 24 remains attached to the outer face of blank portion 11.

After filling in the required data, including signature, if the recipient follows fully the instructions or suggestions contained in the indicia on the inner face of the main sheet, he refolds it in 60 an obvious way to bring the return address 30 to an outer face of the completed package; that is, as shown in Fig. 6, he first refolds the sheet portions 16 and 17 in the same manner as previously, then folds the broad flap 23 (from which the narrow flap 24 has been detached as above) upon the sheet portions 13 and 15 as shown in Fig. 7, and then folds the entire blank along the central line 6 whereupon the original address 35 is enclosed and concealed at the center of the package; the 70 resealing flap 20 is then folded over in an obvious way and secured after moistening its adhesive 28, producing the complete return package as shown in Fig. 8, in which the return address 30 is exposed on one outer face of the package, ready 75 for mailing.

It will be noted that if the original addressee fails to place his signature or name in the space provided on the inner face of the blank, the original sender will nevertheless be able to identify the communication because the blank portion 23 bearing the original address remains attached and can be instantly referred to; so that the invention provides the desirable facility for positive identification of the communication even when the recipient fails to carry out instructions or suggestions and especially fails to affix his name or signature.

80 A further advantage is that after return to the original sender the blank may be folded so that the flap 23 lies against the outer face of the main sheet 1 which is then in rectangular form and may be conveniently filed along with other sheets of the same character or dimensions in any suitable file drawer or jacket for ready reference; and the name and address of the customer, client or the like remains attached, on the flap 23.

85 Other advantages of the structure from advertising or business standpoints will be understood by skilled persons without further explanation.

I claim:

1. A return letter form or the like, comprising a main sheet of rectangular outline having indicia on its inner face, and also having at one side a sealing flap secured thereto and having a marginal edge co-incident with a marginal edge of the rectangular outline, and at the other side a second portion having a marginal edge co-incident with a marginal edge of a rectangular 105 outline, said second portion having an area approximately one-half the area of the rectangular outline, said second portion serving as an address flap, a sealing flap secured to said second portion, the sealing flaps having adhesive and the parts 110 being arranged for folding the blank with the address flap in an outside exposed position or an inside concealed position.

2. A return letter form or the like, comprising a main sheet of rectangular outline having indicia on its inner face, and also having at one side a sealing flap secured thereto and having a marginal edge co-incident with a marginal edge of the rectangular outline, and at the other side a second portion having a marginal edge co-incident with a marginal edge of a rectangular 120 outline, said second portion having an area approximately one-half the area of the rectangular outline, said second portion serving as an address flap, a sealing flap secured to said second portion, the sealing flaps having adhesive and the parts 125 being arranged for folding the blank with the address flap in an outside exposed position or an inside concealed position, the address flap being arranged to receive an original sending address on its outer face.

3. A return letter form or the like, comprising a main sheet of rectangular outline having indicia on its inner face, and also having at one side a sealing flap secured thereto and having a marginal edge co-incident with a marginal edge of the rectangular outline, and at the other side a second portion having a marginal edge co-incident with a marginal edge of a rectangular 140 outline, said second portion having an area approximately one-half the area of the rectangular outline, said second portion serving as an address flap, a sealing flap secured to said second portion, the sealing flaps having adhesive and the parts 145 being arranged for folding the blank with the address flap in an outside exposed position or an inside concealed position, the address flap being arranged to receive an original sending address on its outer face.

the address flap in an outside exposed position or an inside concealed position, the address flap being arranged to receive an original sending address on its outer face, and also having on its outer face an opening line adjacent its joinder to its sealing flap.

4. A return letter form or the like, comprising a main sheet of rectangular outline having indicia on its inner face, and also having at one side 10 a sealing flap secured thereto and having a marginal edge co-incident with a marginal edge of the rectangular outline, and at the other side a second portion having a marginal edge co-incident with a marginal edge of a rectangular outline, said second portion having an area approximately one-half the area of the rectangular outline, said second portion serving as an address flap, a sealing flap secured to said second portion, the sealing flaps having adhesive and the parts 20 being arranged for folding the blank with the address flap in an outside exposed position or an inside concealed position, the blank having imprinted on a lengthwise central portion of its outer face an address to the original sender.

25 5. A return letter form or the like, comprising a main sheet of rectangular outline having indicia on its inner face, and also having at one side a sealing flap secured thereto and having a marginal edge co-incident with a marginal edge of the rectangular outline, and at the other side a second portion having a marginal edge co-incident with a marginal edge of a rectangular outline, said second portion having an area approximately one-half the area of the rectangular outline, said second portion serving as an address flap, a sealing flap secured to said second portion,

tion, the sealing flaps having adhesive and the parts being arranged for folding the blank with the address flap in an outside exposed position or an inside concealed position, the blank having imprinted on a lengthwise central portion of its outer face an address to the original sender, the blank and indicia being so arranged that in one folded condition the address to original sender is outermost and in another condition the first sending address is outermost.

6. A return letter form or the like, comprising a main sheet of rectangular outline having indicia on its inner face, and also having at one side a sealing flap secured thereto and having a marginal edge co-incident with a marginal edge of the rectangular outline, and at the other side a second portion having a marginal edge co-incident with a marginal edge of a rectangular outline, said second portion having an area approximately one-half the area of the rectangular outline, said second portion serving as an address flap, a sealing flap secured to said second portion, the sealing flaps having adhesive and the parts being arranged for folding the blank with the address flap in an outside exposed position or an inside concealed position, the blank having imprinted on a lengthwise central portion of its outer face an address to the original sender, the blank and indicia being so arranged that in one folded condition the address to original sender is outermost and in another condition the first sending address is outermost, the flap bearing the original sending address remaining attached to the blank when the original package is opened.
